UNITED STATES PATENT OFFICE.

LEO HIRSCHFELD, OF NEW YORK, N. Y.

DESIGN FOR A CARTON.

43,928.

Specification for Design.

Patented Apr. 29, 1913.

Application filed January 30, 1913. Serial No. 745,286. Term of patent 14 years.

To all whom it may concern:

Be it known that I, LEO HIRSCHFELD, a citizen of the United States, residing in the city, county, and State of New York, have invented a new, original, and ornamental Design for a Carton, of which the following is a specification, reference being had to the accompanying drawing, forming part thereof and showing my new design.

In the drawing: Figure 1 is a view of a

carton, showing the same in top plan; and Fig. 2 is a side elevation thereof.

I claim:

The ornamental design for a carton, as shown.

LEO HIRSCHFELD.

Witnesses:

W. E. LAWSON,
J. D. CHLINGER.
